The ornamental design for a fluid filled pressure compensation pad for use in a seat cushion, as shown and described.

DESCRIPTION

FIG. 1 is a top plan view of a new design for a fluid filled pressure compensation pad for use in a seat cushion;

FIG. 2 is a bottom plan view;

FIG. 3 is a short side elevational (or edge) view, the opposite short side view being a reverse mirror image thereof; and,

FIG. 4 is a long side elevational (or edge) view, the opposite long side view being a reverse mirror image thereof.
